(57) **CLAIM**

The ornamental design for a blower, as shown and described.

DESCRIPTION

FIG. 1 is a perspective view of a blower showing our new design;

FIG. 2 is a top view of the blower of FIG. 1;

FIG. 3 is a bottom view of the blower of FIG. 1;

FIG. 4 is a back view of the blower of FIG. 1;

FIG. 5 is a front view of the blower of FIG. 1;

FIG. 6 is a left side view of the blower of FIG. 1; and,

FIG. 7 is a right side view of the blower of FIG. 1.

The broken lines shown in the drawings are included to illustrate portions of the blower that form no part of the claimed design.

1 Claim, 7 Drawing Sheets
